UNITED STATES PATENT OFFICE.

THOMAS PEACOCK, OF LONDON, ENGLAND.

FOLDING OR COLLAPSIBLE SUPPORTING STAND.

Application filed May 27, 1922. Serial No. 564,180.

To all whom it may concern:

Be it known that I, THOMAS PEACOCK, a subject of the King of Great Britain, residing at London, England, have invented certain new and useful Improvements in Folding or Collapsible Supporting Stands, of which the following is a specification.

This invention relates to folding or collapsible supporting stands particularly adapted for use with photographic cameras, and has for its object to provide a stand of this character, which in use will form a rigid supporting structure, and when not required for use can be readily collapsed or folded into an extremely compact form convenient for transport, or for use as a walking stick.

According to the invention I provide a folding tripod for adjustably supporting a carrying table or the like for the camera or other object, and I provide bracing members between said carrying table and the legs of the tripod, the bracing members being so connected to the tripod legs as to be capable of adjustment thereon or therein.

The stand may take the form of two folding tripods one supported upon the other so that the legs of the one are capable of sliding on the legs of the other, means being provided for temporarily securing the engaged legs in the adjusted position.

In this particular form, the carrier or table for the camera, may be supported entirely by the bracing members if desired.

One form of stand constructed in accordance with the invention is shown by way of example in the accompanying drawings in which:—

Figure 1 is a front elevation of the complete stand in the open position.

Figure 2 is an enlarged sectional plan view, partly broken away the section being taken on the line A—A of Figure 1.

Figure 3 is a sectional elevation (partly broken away) corresponding to Figure 1, the section being taken on the line B—B of Figure 2.

Figure 4 is an elevation of the stand in the closed position, fitted with end caps, to form a somewhat enlarged form of walking stick.

Figure 5 is an enlarged front elevation of one of the legs of the stand showing more clearly the means for connecting the bracing members thereto.

Figure 6 is a side sectional elevation cor-

responding to Figure 5 the section being taken on the line C—C of that figure.

Figure 7 is a top plan view of the supporting table with the covering plate removed to show a locking slide fitted beneath it.

Figure 8 is a cross sectional elevation on the line D—D of Figure 7, partly broken away.

Figures 9 and 10 are elevational views of the top cap looking from opposite sides thereof.

Figure 11 is a sectional view on the line E—E of Figure 12 and is a similar view to Figure 8 but showing another form of table.

Figure 12 is a plan corresponding to Figure 11, while

Figure 13 is a plan showing the leaves of the table extended.

Figure 14 is a plan of a leaf for another form of table in the opened position.

Figure 15 is a cross section on X—X, Figure 14.

In the form of the invention, a lower folding tripod consisting of three legs 1 pivoted at their upper ends to a common connecting member 2 forming the top of this tripod, and having their lower ends pointed as at 3, is provided to receive slidably the stem 4 of a table or carrier for the camera.

The table or carrier is circular and is formed in two parts, one designated 5 being similar to the connecting member 2, and the other designated 5' consisting of a cover plate serving as the table proper, and the stem consists of a comparatively long rod preferably tubular, connected to the centre of the table and passing through a hole 6 formed in the centre of the common connecting member 2 for the legs 1 of the tripod.

In order to maintain the stem 4 steady and to enable it to be retained in any adjusted position, the connecting member 2 for the legs 1 of the tripod is provided with a guide tube 7 for the stem, said guide tube 7 which extends downwardly from the connecting member 2, having its lower end split as at 8 and screw threaded to receive a clamping nut 9.

Each leg 1 of the tripod is formed with a longitudinal groove 10 in the interior face and with recesses 11, Figure 3, at the upper end somewhat deeper than the grooves 10 so that the legs 1 can be closed together.

about the stem 4 and its clamping nut 9, which are thereby neatly housed between the legs 1 in the folded position thereof.

Each leg 1 of the tripod is also provided with a longitudinal groove 12, the side walls of which are undercut as at 13, the connecting member 2 being cut away correspondingly.

The table or carrier 5 for the camera, has pivoted thereto, in equally spaced relation the upper ends of three bracing members 14, which engage at their lower ends in the groove 12 formed in the exterior faces of the tripod.

These bracing members 14 are preferably rigid, so as to form with the table or support 5 a second folding or upper tripod arranged on the first.

The bracing members 14 are provided at their lower ends with clamping devices 15 so that after the table has been adjusted to the required height the ends of the bracing members 14 can be clamped in the grooves 12 of the tripod legs 1 in their adjusted positions.

Each clamping device 15, preferably comprises two superposed plates 16 and 17 (Figures 5 and 6) carried by the bracing member 14, and arranged in the groove 12 with their side edges beneath the shoulders formed by the undercut 13, the upper plate 16 having flanges 18 which fit slidably between the side faces of the groove 12 above the shoulders, and are adapted to carry between them a transverse pivot pin 19 for an operating lever 20.

The operating lever 20 is provided with one or more, preferably two, pressure transmitting plates 21 of substantially quadrant form, the pivot pin 19 passing freely through these plates.

A slot 22 is formed in the upper plate 16 and when the lever 20 is moved inwardly, the pressure transmitting plates 21 are adapted to bear on the face of the lower plate 17, exposed by the slot 22, thus forcing the plates 16 and 17 apart, and retaining them apart when the lever 20 passes over the dead centre.

The two plates 16 and 17 are then pressed tightly against the under face of the shoulder and the bottom face of the groove 12 respectively, thereby producing the desired clamping effect.

The lower plate 17 has guide pins 23 and 24 which pass loosely through guide apertures formed in the upper plate 16.

The form of table or carrier 5 shown in Figures 7 and 8, is provided with a central recess 25 to receive the head of the camera screw 26 for securing the camera in position thereon, the stem 4 projecting into the central aperture to form an abutment on which the head of the camera screw 26 is adapted to rest. In order to facilitate this

securing operation a slide 27 provided with a key hole slot 28 is fitted in the table (i. e., between the parts 5, 5', one of which is grooved diametrically to receive it) so as to pass therethrough, and the head of the screw 26 is provided with a narrow neck 29 for engagement within the straight portion of the keyhole slot 28.

The camera screw 26 can thus first be screwed into the camera, the slide 27 pulled outwardly, until the enlarged part of the slot 28 coincides with the central aperture of the recess 25, and the camera can then be placed on the table with the head of the camera screw 26 entering the central aperture of the recess 25, and the slide 27 pushed inwardly so that the sides of the straight portion of the slot 28 engage with the neck 29 in the screw head.

The engaging surfaces of the slide 27 and of the head of the camera screw 26 may be bevelled so as to produce a wedge action, thus pulling the camera down tightly on to the table as the slide 27 is pushed in.

In order to guard against loss of the camera screw 26, a wire spring 30 may be fitted in the recess 25 so that one end extends over the central aperture, to one side thereof for engagement in a circumferential groove 31 provided in the head of the screw 26, a washer 32 being fitted in the recess to retain the spring in position.

When the stand is folded or collapsed the bracing members 14 fit into the grooves 12 in the outer faces of the legs 1 of the tripod, flush with the outer surfaces thereof.

Preferably the legs 1 of the lower tripod are each tapered gradually from the upper end downwards and their outer faces, and the corresponding outer faces of the bracing members or legs 14 of the upper tripod are of curved formation laterally, so that in the collapsed or folded position, the stand presents exteriorly the appearance of a tapered rod or pole of circular cross section.

A pointed cap 33 may be fitted by means of a bayonet joint to the lower end of the stand in the folded position, and a suitable head 34 ornamented or not as desired may be removably secured on the upper end, so that the folded stand then presents exteriorly the appearance of a walking stick on a somewhat enlarged scale, as illustrated by Figure 4.

A securing strap 35 may be fixed to one of the legs 1 of the tripod or to one of the bracing members 14, so that it can be passed about the stand in the folded position and fastened for instance by a loop at its end 125 engaging over a stud which secures the strap in position.

In order to enable the head 34 to be locked in position on the folded stand, a cylindrical collar 36 forming part of the head 130

is provided with a T slot 37 and a narrow horizontal slot 38 diametrically opposed, and the slide 27 mounted in the table or carrier 5, 5', for the camera, is reduced in width a short distance in from the outer end as at 39.

The width of the vertical portion of the T slot 37 is slightly greater than the width of the reduced portion of the slide, and the width and depth of the horizontal portion 10 of the T slot 37 and the diametrically opposed narrow slot 38, are slightly greater than the width and depth of the non-reduced portion of the slide.

In applying the head 34, the slide 27 is 15 first pulled outwardly from the table to its full extent to expose the reduced portion, and the head 34 is then fitted on the table or carrier with the vertical side of the T slot 37 disposed adjacent to the side edges 20 of the reduced portion of the slide 27, whereupon the head is pushed downwardly to its full extent. The horizontal portion of the T slot 37 is thus brought opposite to the wider or outer portion of the slide 27, 25 and being of a width slightly greater than the width of this outer portion, allows the slide 27 to be pushed inwardly so that its opposite extremity projects beyond the table or carrier into the narrow horizontal slot 30 38 diametrically opposed to the T slot 37.

In order to provide for a more extensive and therefore steadier support for the camera the cover-plate 5' of the table may be provided with extensible leaves for example 35 in the form shown in Figures 11 to 13 a plurality of leaves 40 are pivoted on rivets 41 to the cover-plate 5' which is cut away to receive them, leaving a central boss 42, the upper surfaces of the leaves are flush 40 with the top of the central boss 42. The outer and inner edges of the leaves 40 are of arcuate form corresponding to the edge of the plate 5' and to the boss 42 respectively, so that when the leaves 40 are in 45 their closed position as indicated in Figures 11 and 12 they lie within the circumference of the cover-plate 5'. The adjacent ends of the leaves are also of corresponding arcuate form to allow the leaves to nest together as shown in Figure 11. A slight projection 43 is provided on each leaf 40 to act as a stop for engagement with the boss 42 when the leaves are extended to 50 their full extent as indicated in Figure 13, ready to support a camera.

In the form shown in Figures 14 and 15 each leaf 40 is in the form of a rectangular plate fitted in a radial groove 44 in the cover-plate 5' so that it can be slidden radially to the centre of the cover-plate 5' into and out of an extended position, the screw 45 entering a slot 46 in the leaf acting as a stop to limit the extension of the leaf.

65 It is to be understood that the invention

is not limited to the particular construction described, as this is given merely by way of example.

I claim:

1. A camera stand comprising an upper 70 tripod having a table and legs pivoted thereto, a lower tripod having a top with legs pivoted thereto and provided with grooves to receive the legs of the upper tripod, and clamps sliding in said grooves for clamping the lower ends of the upper tripod therein when both tripods are distended, the legs of the upper tripod being adapted to lie within the grooves in legs of the lower tripod and flush with the outer surfaces of 80 said grooved legs, when both tripods are folded for the purpose of forming a walking stick, substantially as hereinbefore set forth.

2. An adjustable folding camera stand, 85 comprising a ground engaging tripod having a head and legs pivotally connected thereto adapted for placement in a desired position on the ground, a camera carrying tripod mounted on said ground engaging 90 tripod, comprising a camera supporting table on which a camera is adapted to be mounted having legs pivotally connected thereto, the ends of which are provided for adjustable connection with the legs of the 95 ground engaging tripod, whereby the camera carrying tripod is adapted for adjustment to change the position of the camera without resetting the ground engaging tripod. 100

3. An adjustable folding camera stand, comprising a ground engaging tripod, a camera carrying tripod adapted to have a camera attached thereto, adjustably mounted on the ground engaging tripod, whereby 105 the camera carrying tripod may be adjusted on the ground engaging tripod for changing the position of the camera without affecting the positioning of the ground engaging tripod. 110

4. An adjustable folding camera stand, comprising a ground engaging tripod having a head and legs pivotally connected thereto adapted for placement in a desired position on the ground, a camera carrying 115 tripod mounted on said ground engaging tripod, comprising a camera supporting table on which a camera is adapted to be mounted having legs pivotally connected thereto, the ends of which are provided for 120 adjustable connection with the legs of the ground engaging tripod, whereby the camera carrying tripod is adapted for adjustment to change the position of the camera without resetting the ground engaging tripod, and means carried by the head of the camera carrying tripod cooperating with the head of the ground engaging tripod for holding the camera carrying tripod in a 125 relative centered relation with the ground 130

engaging tripod during adjustment of the former.

5. A camera stand, including a camera supporting table formed with an annular recess opening through the major portion of the upper surface thereof, a plurality of arcuate leaves having one end pivotally connected to the table adapted for interfitting relation in folded position within the recess and formed with stops to limit the outward pivotal movement thereof, whereby the leaves may be moved out of the recess to the outer pivotal position for increasing the size of said table.
- 15 6. An adjustable folding camera stand, comprising a ground engaging tripod having a head with legs pivoted thereon adapted to be folded into interfitting relation to form a cylindrical stick, said legs being provided with grooves, and a camera carrying tripod having a head adapted for connection with a camera to support the same of substantially the same size as the head of the ground engaging tripod and

legs pivoted thereto adapted to fit within 25 the grooves of the legs of the ground engaging tripod, said camera carrying tripod being mounted on and adjustable with respect to the other tripod for changing the position of the camera when the tripods are in 30 extended relation, the head of said camera carrying tripod contacting with the head of the other tripod and the legs fitting wholly within the grooves of the ground engaging tripod when said tripods are in 35 folded relation.

7. A folding camera stand, including a camera carrying tripod adapted to be folded and having a camera supporting table, a cap for covering the table and upper end 40 of the tripod in folded position, a locking member slidably mounted in the table for removably locking a camera to the table and for locking the cap on the tripod.

In testimony whereof I have signed my 45 name to this specification.

THOMAS PEACOCK.
